DAMPENER FOR LITHOGRAPHIC PRINTING

Thomas Peter Brannigan, Gordon Harold Raison,
and William Henry Yoder, Detroit, Mich., as-
signors to General Motors Corporation, Detroit,
Mich., a corporation of Delaware

No Drawing. Application June 30, 1941,
Serial No. 400,568

13 Claims. (Cl. 106—2)

This invention relates to dampening fluid for lithograph plates and stones. Lithograph plates or stones for printing are prepared by throwing light through a photographic negative onto a film of sensitized albumen. The light insolubilizes the portions of the colloid albumen. The plate is then rolled up with a greasing material such as beeswax and sometimes lamp black. This sticks to the portions of the gelatin or albumen which have been insolubilized. The soluble portions of the colloid are then washed off, and the image appears in the greased spots which are formed of dots by reason of the use of a screen. The size of the dots determines the shading.

A deep form of lithography is described and claimed in the Grass Patent No. 1,155,342 in which a positive is used and the light passed through onto a sensitized film of albumen and the portions of the plate bearing the image are slightly etched by a suitable etching fluid. The etched portions are filled with nitrocellulose varnish which serves to hold the ink.

Wood graining on metal is usually done by the photogravure process described and claimed in the Henry Patent No. 1,548,465. In the photogravure process the image is formed by cells in the copper plates of more or less depth, depending upon the tone, the darker the image the deeper the cell and more ink that will be poured on. The printing, of course, is not done directly from a metal plate or roll onto the metal to be grained, but is done by a transfer roll of gelatin or rubber.

Offset printing by lithograph has also heretofore been used for graining metal. However, it has been usual to use a number of color plates, that is, separate impressions are made for each color desired in the final work. Consequently, several photographs are taken through color screens, one for each color and separate plates or stones are made for each color.

In lithography the grease or varnish catches and holds the ink and the rest of the plate is dampened with water by first rolling the plate with a wet roll. We have found that with ordinary wetting or dampening solutions the line of demarcation between the greased or varnished image portions and the wet portions of the plate that are to repel the ink, are not clear cut enough to produce satisfactory results in graining. We have found a dampening liquid which we believe is superior for wetting the blank portions of the stone or plate and which affords a much cleaner line of demarcation between the

image and the blank portions. This solution is made of:

Water	gallons	1
Aerosol	cubic centimeters	5
Ammonium dichromate	grams	40
Gum arabic	ounces	2

Potassium dichromate or sodium dichromate may be substituted for ammonium dichromate.

10 The dichromate acts as a mild etching fluid for keeping the plate clean and this sometimes eats into the plate. The gum arabic fills in the plate so roughened and keeps it smooth and water absorbent. The Aerosol is a commercial wetting agent made by the American Cyanamid & Chemical Corporation. Commercial wetting agents are now on the market and there are several of these which may be purchased and will probably do equally, or nearly as well as the aerosol.

15 Aerosol comes in four groups; the O. S. group, which is defined as the alkyl aryl sulphonate, and the O. T., N. A. and A. Y. groups are sulphonated esters of dicarboxylic acid. The point is to provide a wetting fluid of great penetrability. This serves to cause the dampening fluid to readily spread and immediately reach clear to the margin of the image, whether it be a grease or cellulose varnish. The wetting fluid is a fluid that has very little or no surface tension.

20 When the wetting fluid does not reach right up to the body of the image, then the ink will often spread slightly onto the portions of the plate adjacent the image and give a blurred effect.

25

30 35 We appreciate that dichromate such as potassium dichromate and gum arabic and water have been used in dampening compounds, but so far as we know, these have never been combined from a wetting agent such as aerosol or its equivalents.

40 What we claim is:

1. A dampener for lithographic printing or graining which comprises, a solution of water, ammonium dichromate, gum arabic and a wetting agent having penetrability relatively greater than water.

45 2. A dampener for lithographic printing or graining which comprises a solution of water, an alkaline dichromate and a wetting agent having relatively great penetrability.

50 3. A dampener for lithographic printing or graining which comprises water, a solution of a mild etching fluid, a wetting agent having little surface tension and gum arabic.

4. A dampener for lithographic printing or

graining which comprises a solution of water, a wetting agent having relatively great penetrability and a mild etching fluid.

5. A dampener for lithographic printing or graining which comprises a solution of water and a wetting agent selected from the group which consists of alkyl aryl sulphonates and the esters of sulphonated dicarboxylic acid.

6. A dampener for lithographic printing or graining which comprises a solution of substantially one gallon of water, five cubic centimeters of a wetting agent having relatively great penetrability, forty grams of a mild etching fluid and two ounces of gum arabic.

7. A dampener for lithographic printing or graining which comprises a solution of substantially one gallon of water, five cubic centimeters of a low surface tension liquid, forty grams of ammonium dichromate and two ounces of gum arabic.

8. A step in lithographic printing or graining which comprises wetting the lithographic printing plate or stone with a solution of water, ammonium dichromate, gum arabic and a wetting agent having relatively great penetrability.

9. A step in lithographic printing or graining which comprises wetting the lithographic printing plate or stone with a solution of substantially one gallon of water, five cubic centimeters of a wetting agent having a relatively low surface tension, forty grams of ammonium dichromate and two ounces of gum arabic.

10. A step in lithographic printing or graining which comprises wetting the lithographic printing surface with a solution of water, an etching fluid selected from the group consisting of po-

tassium, ammonium and sodium dichromates, a wetting agent selected from the group consisting of alkyl aryl sulphonates and sulphonated esters of dicarboxylic acid.

11. A step in lithographic printing or graining which comprises wetting the lithographic printing surface with a solution of water, an etching fluid selected from the group consisting of potassium, ammonium and sodium dichromates, a wetting agent selected from the group consisting of alkyl aryl sulphonates, sulphonated esters of dicarboxylic acid and gum arabic.

12. A step in lithographic printing or graining which comprises wetting the lithographic printing surface with a solution of substantially one gallon of water, substantially forty grams of an etching fluid selected from the group consisting of potassium, ammonium and sodium dichromates, substantially five cubic centimeters of a wetting agent selected from the group consisting of alkyl aryl sulphonates and sulphonated esters of dicarboxylic acid.

13. A step in lithographic printing or graining which comprises wetting the lithographic printing surface with a solution of substantially one gallon of water, substantially forty grams of an etching fluid selected from the group consisting of potassium, ammonium and sodium dichromates, substantially five cubic centimeters of a wetting agent selected from the group consisting of alkyl aryl sulphonates, sulphonated esters of dicarboxylic acid and substantially two ounces of gum arabic.
